UNITED STATES PATENT OFFICE.

CLINTON EARL BERNARD, OF KANSAS CITY, MISSOURI.

APPARATUS FOR THERMAL SCALP TREATMENT.

Application filed September 2, 1924. Serial No. 735,392.

To all whom it may concern:

Be it known that I, CLINTON E. BERNARD, a citizen of the United States, residing at Kansas City, in the county of Jackson and State of Missouri, have invented a new and useful Apparatus for Thermal Scalp Treatment, of which the following is a specification.

This invention has reference to an apparatus for thermal scalp treatment.

An important object of the invention is to provide a device of this character which may be readily and easily operated by persons unfamiliar with devices of this character.

A further object of the invention is to provide a device of this character which when in operation will act to supply hot or cold air to the head of the user, means being provided for maintaining the air at a predetermined temperature.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view disclosing a scalp treating device constructed in accordance with the invention.

Figure 2 is a vertical sectional view therethrough.

Figure 3 is a bottom plan view thereof, the cover being removed.

Figure 4 is a sectional view taken on line 4-4 of Figure 2.

Referring to the drawing in detail, the device includes a body portion box-like in formation and comprising an outer section 5 and an inner section 6.

The inner section 6 is spaced from the body section 5, the space between the sections 5 and 6 being designed to accommodate a suitable insulating material such as cork or the like so that the temperature within the device will be held at an even degree while said device is in use.

A coil indicated at 8 is positioned within

the inner casing, the pipe 9 leading to the coil 8 acting as the inlet pipe, while the pipe 10 at the opposite side of the coil acts as the outlet pipe. Within the inner section is a head piece 11 which is constructed of flexible material such as felt or the like to protect the head of the user during a treatment.

The lower end of the device is open so that the device may be placed on the head of the user, the felt padding material acting to close the space between the user's head and the inner casing so that the cold air will be confined to the inner casing.

The cover is indicated at 12 and is held in its active position by means of the securing members 13 which may be moved to disengage the closure and allow the closure to be removed.

An operating handle 14 is formed on the closure so that the closure may be readily and easily disengaged.

In the use of the device, cold air from a suitable refrigerating plant is passed into the coil 8 to reduce the temperature to a predetermined degree. The cover is now removed and the device now positioned on the head of the user where the head of the user comes in direct contact with the cold air within the device.

It is contemplated that a thermostat may be employed within the casing to control the passage of cold air from the refrigerating plant to the interior of the device.

While I have described the device as being used by passing cold air through the coil of the device, it is to be understood that hot air may be passed through the coil if desired, for treating the head.

I claim:

In a device of the character described, a body portion, said body portion having an open end, an inner section supported within the body portion, a pipe extending through the body portion, a coil communicating with the pipe to receive a cooling medium, a head piece having a central opening and formed of resilient material to permit the body portion to be positioned over the head of the user, and a removable closure for normally closing the open end of the body portion.

In testimony that I claim the foregoing as my own, I have hereto affixed my signature.

CLINTON EARL BERNARD.
